[57] CLAIM

The ornamental design for a front bezel for an upright computer, as shown and described.

DESCRIPTION

FIG. 1 is a front elevational view of a front bezel for an upright computer showing my new design;

FIG. 2 is a rear elevational view of the bezel of FIG. 1;

FIG. 3 is a top plan view of the bezel of FIG. 1;

FIG. 4 is a bottom plan view of the bezel of FIG. 1;

FIG. 5 is a right side elevational view of the bezel of FIG. 1 showing an attached upright computer in phantom;

FIG. 6 is a left side elevational view of the bezel of FIG. 1; and,

FIG. 7 is a front perspective view of the bezel of FIG. 1 showing an attached upright computer in phantom.

The computer is shown in broken lines in FIGS. 5 and 7 for illustrative purposes only and forms no part of the claimed design.
